UNITED STATES PATENT OFFICE.

JARED MARIS, OF COLUMBUS, OHIO.

DESIGN FOR A SHELL-BAND FOR HUBS.

SPECIFICATION forming part of Design No. 16,344, dated October 20, 1885.

Application filed July 22, 1885. Serial No. 172,342. Term of patent 14 years.

To all whom it may concern:

Be it known that I, JARED MARIS, a citizen of the United States, residing at Columbus, in the county of Franklin and State of Ohio, have invented and produced a new and original Design for Shell-Bands for Hubs, of which the following is a specification, reference being had to the accompanying drawings, forming part thereof.

10 My invention relates to a design for the ornamentation of the end or ends of a shell-band for a wheel-hub; and it consists in facets around the outer surface of the band near one or both ends, whereby the outer surface or the 15 periphery of the band at one or both ends, instead of being round or circular, is angular, being made up of a series of facets.

In the accompanying drawings, Figure 1 is a plan view of a hub having a shell-band thereon, the latter having the facets at both ends. Fig. 2 is an end view of a band, and Fig. 3 is a view of a shell-band having facets on the outer end only.

The facets *a* are either plane or concaved, and extend inwardly from one or both ends of the band *A*, and may be in the form of equilateral or isosceles triangles, or may be half oval in shape, or any equivalent form. The facets may join at their bases; or they may be slightly separated, if so desired.

Having fully described my design, what I claim as new, and desire to secure by Letters Patent, is—

1. In a design for the shell-band of a wheel-hub, the ornamentation of the same, consisting in a series of facets on the periphery of the band at one end thereof, as shown and described.

2. In a design for the shell-band of a wheel-hub, the ornamentation of the same, consisting in a series of facets on the periphery of the band at both ends, as shown and described.

JARED MARIS.
